UNITED STATES PATENT OFFICE

138,469

DESIGN FOR AN AIRPLANE

Ellis V. Eichman, Brownsville, Tex.

Application September 9, 1943, Serial No. 111,079

Term of patent 14 years

(Cl. D71—1)

To all whom it may concern:

Be it known that I, Ellis V. Eichman, a citizen of the United States, residing at Brownsville, in the county of Cameron and State of Texas, have invented a new, original, and ornamental Design for an Airplane, of which the following is a specification, reference being had to the accompanying drawing, forming part thereof, wherein:

Fig. 1 is a top plan view of an airplane embodying my new design;

Fig. 2 is a front elevational view of said airplane design; and

Fig. 3 is a side elevational view showing the design.

The dominant features of the airplane of my design reside in the portions shown in full lines in the drawing.

I claim:

The ornamental design for an airplane, as shown and described.

ELLIS V. EICHMAN.
